UNITED STATES PATENT OFFICE.

EDWARD CRAIG, OF ST. JOSEPH, MICHIGAN, ASSIGNOR TO SARANAC MACHINE CO., OF ST. JOSEPH, MICHIGAN, A CORPORATION OF MICHIGAN.

BOOK-STITCHER MACHINE.

1,253,354.

Specification of Letters Patent. Patented Jan. 15, 1918.

Application filed December 27, 1909. Serial No. 534,908.

To all whom it may concern:

Be it known that I, EDWARD CRAIG, a citizen of the United States of America, and resident of St. Joseph, Berrien county, Michigan, have invented a certain new and useful Improvement in Book-Stitcher Machines, of which the following is a specification.

My invention relates to stapling machines of the kind used in stitching books or stapling the corners of boxes.

The object of my invention is to provide an improved and highly efficient machine for this purpose.

It is also an object to provide certain details and features of construction and combinations tending to increase the general efficiency and desirability of a machine of this particular character.

To these and other useful ends, my invention consists in matters hereinafter set forth and claimed.

In the accompanying drawings,

Figure 1 is a front elevation of a stapling machine embodying the principles of my invention.

Fig. 2 is a vertical section on line 2—2 in Fig. 4.

Fig. 3 is a detail view of the clutch.

Fig. 4 is a side elevation of the machine shown in Fig. 1.

Fig. 5 shows another form of back gage.

Fig. 6 is a rear view of the parts shown in Fig. 5.

Fig. 7 is an enlarged vertical section on line 7—7 in Fig. 4.

Fig. 8 is an enlarged horizontal section on line 8—8 in Fig. 7.

Fig. 9 is an enlarged horizontal section on line 9—9 in Fig. 7.

Fig. 10 is a vertical section on line 10—10 in Fig. 9.

Fig. 11 is a perspective of the removable disk cutter for severing the wire.

Fig. 12 is a vertical section on line 12—12 in Fig. 7.

Fig. 13 is a perspective of the member that carries the said disk cutter.

Fig. 14 is a perspective of the plate that holds the clench blocks in place.

Fig. 15 is a vertical section on line 15—15 in Fig. 7.

Fig. 16 is a vertical section on line 16—16 in Fig. 7.

Fig. 17 is a vertical section on line 17—17 55 in Fig. 7.

Fig. 18 is an enlarged section on line 18—18 in Fig. 4.

Fig. 19 is a perspective of the cam that carries and operates the staple former. 60

Fig. 20 is a perspective of the cam that carries and operates the staple driver.

Fig. 21 is a perspective of the staple former.

Fig. 22 is a perspective of the staple 65 driver.

Fig. 23 is an enlarged front view of the indicating device for the feed mechanism adjusting device.

Fig. 24 is an enlarged fragmentary view 70 of the loop bar.

Fig. 25 is a detail sectional view of the front portion of the table, showing another form of side gage, whereby the work is properly positioned on the table to insure 75 driving of the staples at the proper points therein.

As thus illustrated, the operative parts of the machine are supported on an upright frame or standard A having a base a adapted to rest upon the floor. The tilting table or rest B for the work is supported on the arm a' of said standard. Said table consists of two parts, b and b', rigidly connected and disposed at an angle to each other. The table is pivotally mounted at b² upon the block b³ which slides up and down in the bearing b⁴ on the end of the arm a'. This block b³ is provided with a threaded bore b⁵ which is engaged by the screw b⁶, which latter is held in the bearing b⁷ depending from the front of the bearing b⁴. The said screw is provided at its lower end with a hand wheel b⁸ by which it is rotated. By this screw the table B can be raised and lowered, in accordance with the character of the work. The pivot b² consists of a bolt, see Fig. 7, whereby the table can be tilted and held in different positions, as indicated in Fig. 4. The member b⁹, 100 which is pivoted on the block b³, and which is connected with the table by a spring b¹⁰, supports the table when in the position shown in dotted lines in Fig. 4. Below the

table the plates b^{11} and b^{12} are removably set in the top of the block b^3 . The front plate b^{11} is shown in Fig. 14, and the other plate is exactly the same except for the central opening. The clench blocks or anvils b^{13} are pivoted between these plates b^{11} and b^{12} , and are adapted to deflect the two points of the staple toward each other. For this purpose, and to insure the desired accuracy of clenching, the said anvils b^{13} are adapted to be swung up and down about their pivots by the vertically movable member b^{14} . The lower end of this member b^{14} is threaded internally to engage the upper end of the threaded rod b^{15} , which latter extends downward through the screw b^6 . A lever C is pivoted on the frame or standard A and provided with a pivoted socket piece c which is threaded to engage the lower threaded end of the rod b^{15} . The upper and lower ends of this rod b^{15} are thus given a right and left thread, and its middle portion is flattened at b^{16} , where it passes through the hand wheel b^8 . Thus when this hand wheel is rotated it does two things, as follows: It moves the table up and down, and also in effect lengthens and shortens the rod b^{15} , whereby the raising and lowering of the table does not disturb the relation between the anvils and the top of the member b^{14} . The pitch of the different threads is such that for any given adjustment of the table the rod b^{15} is correspondingly varied in length. By the lever C the anvils b^{13} are raised to bend the staple points toward each other. A pivoted locking handle b^{17} is arranged for holding the plate b^{11} in place. By swinging this handle to one side the said plate can be removed, together with the anvils and the back plate b^{12} . It will be seen that this handle clamps the plates b^{11} and b^{12} against the vertical shoulder b^{18} on the top of the block b^3 . An opening b^{19} in the top of the table permits the work to engage the top of the blocks b^{11} and b^{12} , and is large enough to permit the desired movement of the table. It will be seen that the tops of said blocks b^{11} and b^{12} are beveled to engage in the corners of a box or book, in the well known manner.

A gage or back stop D, (see Fig. 4), is adapted to rest upon the table, as shown in dotted lines, to gage the position of the work thereon. This gage or back stop D is adjustably mounted upon swinging rods d , which are pivoted at d' to the frame A. When the position of the table is changed, the gage can be lowered, as shown. If desired, the gage can be made as shown in Fig. 5. In this case the gage D is mounted upon the rods d^2 , which are held in the clamps d^3 . The rods d^4 are also held in these clamps, and have their upper ends pivoted at d^5 . Thus the gage, by lowering the

screw d^6 of the clamp, can be moved forward and back and up and down.

A swinging stock gage E is pivoted upon the side of the stapler head F and held normally raised by a spring e. This gage can be swung down, by a handle, and by then raising the table until the stock engages the lower end of said gage the right adjustment will be obtained for any given thickness of stock or material.

The front plate f of the stapler head is removably held in place by a lock f' which has a handle f'' for rotating it into and out of engagement with the front of said plate. The said stapler head comprises a staple former f² and a staple driver f³, both of which can be removed or turned end for end. The said former has holes f⁴ adapted to engage the pins f⁵ on the shank f⁶ of the cam f⁷. The driver is provided with holes f⁸ adapted to engage the pin f⁹ on the shank f¹⁰ of the cam f¹¹. The cam f⁷ has a shank f¹² adapted to engage the upper end of the staple former f², and the cam f¹¹ has a similar shoulder f¹² adapted to engage the top of the dryer f³. The driver f³ is formed to slide up and down in the former f², whereby the latter acts as a guide for the driver. The said staple driver and former, and their respective cams, are fitted within the stapler head F and slide up and down therein. See Fig. 12. The cam f⁷ has a cam opening f¹⁴ which is engaged by the roller f¹⁵ on the wheel f¹⁶ on the shaft f¹⁷, which roller also engages the cam opening f¹⁸ in the cam f¹¹. The wheel f¹⁶, when rotated operates the staple former and driver, and the shape of the openings f¹⁴ and f¹⁸ is such that the driver has the usual extent of movement over the staple former—that is to say, the driver moves downward after the former stops moving. The cutting member G is fitted to slide up and down at one side of the staple former and driver, and has a spring g for raising it. The upper end of this member G is beveled at g' to engage the roller g² on the cam f¹⁹, whereby the said member G is actuated at the proper time to cut the wire. This member G has a groove or recess g³ which holds the round or washer-like knife g⁴, the latter bearing at its other side against the plate g⁵. The horizontally sliding block H is mounted on the staple head, and has the knife g⁴ removably held thereto by the plate h, whereby horizontal movement of this block H causes the knife g⁴ to move along the groove g³, so that the length of wire cut off may be varied at will. The knife g⁴ can be turned around when one edge becomes worn, so as to bring a sharp edge into position to engage the wire. The anvil I supports the wire while the former f² is bending the same into the shape of a staple. This anvil or loop bar I is removably mount-

ed on the lever i which is pivoted at i' and provided at its upper end with a roll i^2 adapted to be engaged by the cam i^3 on the back of the cam f^{11} . When the roller i^2 engages this cam i^3 the loop bar I falls back by gravity, and the staple is supported by the element i^4 until driven by the driver. This element i^4 is hook-shaped and pivoted upon the end of the loop bar, so as to readily receive the staple. When the driver moves down, it engages the staple and thereby pushes the element i^4 back against the tension of the spring i^5 , which latter returns the said staple support i^4 to normal position when the driver and former return to normal position. The wire is fed through a tube J and under the hold back device j , which latter consists of a roll with fine teeth, and a screw j' for holding it in different positions. Then the wire passes across the rest j^2 , which is on the lower end of an arm j^3 , and under the feed dog j^4 pivoted thereon. The arm j^5 is pivoted at j^6 and provided with a lower end portion adapted to actuate the dog j^4 . This arm j^5 is rigid with an arm j^7 that has a roll j^8 , which latter is engaged by the cam f^{20} to feed the wire at the proper time. A spring j^9 serves to keep the roll j^8 on the cam f^{20} , and to retract the feed dog j^4 . A spring j^{10} presses against the back of the arm j^5 to make it move under friction, so that the dog j^4 will work back and forth to grip and release the wire, the wire being clamped by the dog upon the rest j^2 when the feed arm j^5 moves toward the staple driver. A bumper K limits the back stroke of the feed arm and dog, and is movable with, but twice as fast as, the block H . This is accomplished by a screw L which is adapted to move or adjust the bumper K and the block H toward and away from the staple driver. It will be seen that this screw has a relatively large screw threaded portion l which operates the bumper, and a relatively small screw threaded portion l' which operates the cutting device support or block H , whereby the distance between the bumper and said block is changed or varied. In this way the feed is varied to vary the length of the staples. Thus the wire is pulled through the tube J and pushed into the tube M that leads to the staple forming mechanism. The proper length is then cut off by the disk knife g^4 and driven into the work on the table. The indicator N shows the correct adjustment of the feed. It slides with the block H .

The tube J is springy and so held at its lower end that it springs enough to take up the slack in the wire, owing to any over-feed from the reel O , and this prevents the wire from getting over the rim of the reel.

The knife P can be operated by hand to cut off the wire should anything go wrong with the feed.

The arm C is actuated by a cam Q on the shaft, through the medium of the connections q and q' . The clutch R is controlled by a lever r and has a brake r' which prevents operation by momentum.

From the foregoing it will be seen that I provide an improved and highly efficient machine for stapling books or boxes or other articles.

The table B has side gages X which are 75 movable along a rod x , and which are adapted to be secured in any position thereon by a thumb screw x' . By means of these gages, the work can be positioned on the table and held in position for receiving the staples. 80

In Fig. 25, I have shown another form of side gage for the front of the table. In this case the gage V is pivoted at y upon a block y' , which latter is adapted to slide in a dove-tail groove y^2 formed in the lower 85 surface of the table. This block y' is adapted to be held in any desired position in said grooves—that is to say, at any point along the length of the groove, by the set screw or other fastening device y^3 , whereby the 90 said front gage can be moved along the front of the table.

By means of these front gages, and in conjunction with the back stop or rear gage previously described, the work is accurately 95 held in position on the table.

My invention is not limited to the exact construction shown and described.

What I claim as my invention is:

1. In a stapling machine of the class disclosed, a wire cutting device consisting of a disk or plate having an outer cutting edge, a member for actuating said disk or plate bodily, and means for moving the plate or disk laterally to vary the length of the wire 105 cut off, said member having a groove in which said disk or plate is rotatable in the plane thereof, and in which it is movable sidewise by said means.

2. In a stapling machine of the class disclosed, a wire cutting device for the wire, a feed device, a back stop for the feed device, and means for adjusting the back stop and cutting device, including a single screw which controls said device and stop, said 115 screw having means for varying the distance between the back stop and cutting device.

3. In a stapling machine of the class disclosed, a loop bar, means for forming the 120 staple on said bar, a spring held carrier mounted on the end of said loop bar to receive the staple therefrom, and a driver arranged to depress the said carrier and drive the staple.

4. In a machine of the class disclosed, adapted for use as a book stapling machine, a removable clenching device, means for holding said device in operative position, including a removable front plate therefor, 130

- bearing flatwise against said device, a back plate similar to said front plate, a pivoted retainer for the front plate, and means, substantially as described, for coöperating with 5 the aforementioned elements to staple the book, comprising means for automatically feeding the staple wire.
5. In a machine of the class disclosed, adapted for use as a book stapling machine, 10 swinging rods, a back stop or gage for the work, adjustably mounted on said swinging rods, whereby said back stop is movable into operative position, means for coöperating with the aforementioned elements to staple 15 the book and including devices for automatically feeding the staple wire, and a tilting work support movable into engagement with said stop when the latter is raised into position.
- 20 6. In a machine of the class disclosed, a staple driver constructed and arranged to be turned end for end, a roller, and an actuating cam plate for said staple driver, provided with a single pin for selectively engaging different holes in said driver, together 25 with means whereby said cam is actuated by the said roller.
7. In a machine of the class disclosed, a staple former adapted to be turned end for end and provided with a longitudinal groove, 30 a reversible staple driver working in said groove, a roller, an actuating cam plate for said staple former, provided with pins for engaging holes in said former, which said cam plate is actuated by said roller, and means for operating said driver.
- 40 8. In a machine of the class disclosed, a box or housing, a pair of flat cams mounted therein, held flatwise together, a staple driver for one cam, a staple former for the other cam, disposed flatwise together and between the depending shanks of said cams, means for actuating said cams, and a flat front plate secured to said box or housing, 45 whereby the said parts are all easily accessible and easily removable.
- 50 9. In a machine of the class disclosed, a wire feed mechanism, a staple forming and driving mechanism, a wire retarding device, and means for cutting off the wire before it reaches the said feed mechanism, for the purpose described, consisting of a manually operable cutting device disposed between the retarding device and said mechanism.
- 55 10. In a machine of the class disclosed, adapted for use as a book stapling machine, a pair of plates, a pair of clench blocks pivoted between the two plates, means for adjusting said blocks, a table comprising sides 60 arranged at an angle to each other so as to form a corner at their meeting edges and associated with said blocks, means for adjusting said table, means for actuating said blocks, a single device for operating both of 65 said adjusting means, and means, substan-

tially as described, for coöperating with the aforementioned elements to staple the book, one said plate being removable, and a retainer for said removable plate.

11. In a machine of the class disclosed, 70 adapted for use as a book stapling machine, a pair of clench blocks pivoted between two plates, a device for actuating said blocks, a flat plate covering the said blocks, affording easy access thereto, a handle provided with 75 means for removably locking said plate in position, a support upon which said handle is pivoted below said plate, and means, substantially as described, for coöperating with the aforementioned elements to staple the 80 book, and means for positioning said plate.

12. In a machine of the class disclosed, a stapling mechanism provided with a cutting member, means for holding the wire in position to be cut by said member, a rotary 85 shaft, a rotary cam on said shaft for directly actuating said cutting member, spring means associated therewith for keeping said cutting member in engagement with said cam, a cutter on said member, and means for adjusting 90 said cutter sidewise in said member to vary the length of the staple.

13. In a machine of the class disclosed, a wire cutter, a block for adjusting said cutter, upon which the same is mounted to reciprocate, a screw for adjusting said block to vary the length of the wire cut off by said cutter, a staple wire feed device, a bumper for the feed device, and means on said screw for manually adjusting said bumper to 100 change the position thereof, said screw connecting the bumper and block together.

14. A stapling machine comprising a staple former, a staple driver, a movable anvil member coöperating with said former 105 to make the staple, and mechanism to support the staple after leaving said anvil, said mechanism including an element carried by said member to receive the staple, and a spring carried by said member and arranged to yieldingly present said element in the path of said driver.

15. A stapling machine comprising a staple former, a staple driver, a movable anvil coöperating with said former to make 115 the staple, and mechanism to support the staple after leaving said anvil, said mechanism including a pivoted element to receive the staple, a spring arranged to yieldingly present said element in the path of said driver, and a rod inclosed by said spring and pivoted on said element.

16. A stapling machine comprising a staple former, a staple driver, a movable anvil coöperating with said former to make 120 the staple, and mechanism to support the staple after leaving said anvil, said mechanism including a pivoted element to receive the staple, and a spring arranged to yieldingly present said element in the path 130

of said driver, said element being supported by said anvil.

17. A stapling machine comprising a staple former, a staple driver, a movable anvil coöoperating with said former to make the staple, and mechanism to support the staple after leaving said anvil, said mechanism including a pivoted element to receive the staple, and a spring arranged to yield-

ingly present said element in the path of said driver, said anvil having a movable support for the pivot thereof.

Signed by me at St. Joseph, Michigan, this 22d day of December, 1909.

EDWARD CRAIG.
